Attorney.

UNITED STATES PATENT OFFICE.

CLARENCE A. VETTER, OF PITTSBURGH, PENNSYLVANIA.

LAMP-SOCKET.

1,209,910.

Specification of Letters Patent. Patented Dec. 26, 1916.

Application filed January 16, 1915. Serial No. 2,562.

To all whom it may concern:

Be it known that I, CLARENCE A. VETTER, a resident of Pittsburgh, in the county of Allegheny and State of Pennsylvania, have 5 invented a new and useful Improvement in Lamp-Sockets, of which the following is a specification.

This invention relates to sockets for incandescent lamps, and particularly to the 10 connection between the cap and shell thereof.

The object of the invention is to provide a simple connection which enables the cap and shell to be connected in any position relative to each other and to be easily 15 disconnected by simple manipulation.

The invention comprises the construction and arrangement of parts hereinafter described and claimed.

In the drawings, Figure 1 represents a 20 side elevation, partly in section, of the cap; Fig. 2 is a side elevation of the shell; Fig. 3 is a plan view of the shell; Fig. 4 is a detail section on the line 4—4, Fig. 2; and Figs. 5 and 6 are enlarged detail views, 25 showing the cap and shell connected and the manner of disconnecting the same.

The cap shown in the drawings is formed in the usual manner of pressed sheet metal and is provided with a body portion 1 terminating in an annular skirt or flange 2, so arranged as to form an annular shoulder 3 at the junction between the skirt and body and which forms an abutment to limit inward movement of the shell into the cap. 30 The skirt is provided with a plurality of openings 4, which are repeated at frequent intervals around its periphery, and which may be formed in any suitable manner, either in a separate member attached thereto, 35 or in the same sheet as the body 1. As shown, said openings are formed in the skirt 2, which is surrounded by a ring 5 having its edges rolled or turned over the edges of the skirt to secure the same thereon. 40 This ring covers and protects the openings 4 and gives the cap a neat and pleasing appearance. The openings 4 may be of any suitable shape but are shown as substantially 45 rectangular, having straight longitudinally extending edges 6 and outer and inner transverse edges 7, 7^a, all of which are sharp or abrupt and are formed by merely punching out the material of the skirt, and leaving solid portions, marked 18, between each two openings. 50

The shell 8 is of the usual construction,

being shaped to receive the body or base of the lamp socket and provided with the usual longitudinal slot 9. Said shell is provided with suitable locking means for coöperating 60 with the openings 4 in the socket cap. For this purpose it is provided with a suitable number of projections 10, spaced at suitable intervals around the shell and formed by punching up small portions of the metal 65 from the body thereof. This is done in a manner to form a sharp or abrupt back edge 11 on each projection, from which the surface of the projection is inclined toward the general surface of the shell and gradually 70 merges therewith. This produces an inclination on each projection in two directions, namely from the back or end edge 11 toward the end edge 12 of the shell, and also in both directions peripherally of the shell. 75

The shell and cap are assembled by inserting the shell into the cap and pushing it to place. The inclined portions of the projections 10 engage the end edges of the cap skirt and as the metal of the shell will yield 80 sufficiently for this purpose, pass into the openings 4 in the skirt, the resiliency of the shell then causing said projections to spring outwardly into said openings and secure the shell to the cap. The abrupt back edges 11 85 of the projections 10 normally prevent escape of the shell from the cap and produce a firm and secure connection therebetween. By using three projections spaced at substantially regular intervals around the shell, 90 as shown, the cap and shell will not separate by side bending pressure on one thereof, such as is caused by the weight of the socket and lamp when the lamp is in a horizontal position in a side wall bracket. No matter 95 what position the socket may be in lateral pressure on the shell in any direction is resisted by one or two abrupt shouldered engagements between the cap and shell. This 100 feature avoids putting on special locking or securing devices for this purpose, which is necessary when the locks or latches between the cap and shell are diametrically opposite each other.

To enable the shell and cap to be readily 105 disconnected by simple manipulation the projections 10 may be located on the shell in such position that the distance between their abrupt back edges 11 and the end edge 12 of the shell is less than the distance between the outer end edges 7 of the openings 4 and the circular abutment 3 of the cap. 110

When the shell and cap are interlocked with each other, as shown in Fig. 5, the end edge 1 of the shell is therefore spaced away from the abutment 3. This enables the shell to be pushed or telescoped farther into the cap until its end edge 12 strikes the abutment 3, as shown in dotted lines at A, Fig. 6. In this position the inclined portions of the projections 10 have ridden up over the inner end edges 7^a of the opening 4, so that the metal of the shell at each projection has been forced slightly inwardly toward the axis of the socket. By then relatively turning the cap and shell the projections 10 may be caused to ride up onto the smooth inner surface of the skirt of the cap. The cap and shell may then be disconnected by pulling them apart, which causes the projections 10 to slide over the solid portions 13 of the skirt between the openings 4. It is by no means essential, however, to have the latching portion of the shell shorter than the skirt of the cap, as described. If the abrupt edges 11 of the shell projections are the same distance from the end edge of the shell as the distance between the outer edges 7 of the openings 4 and the abutment 3, then the cap and shell may be disconnected by a combined twisting motion, that is, a slight rotation to cause the projections to ride up on the solid portions 13 and a pull to separate the shell and cap.

The construction described is very simple and can be manufactured at low cost. It wholly avoids the necessity of pressing in a portion of the shell in disconnecting the shell and cap, and which frequently so deforms one or the other of these parts as to make the socket useless. It also enables the shell and cap to be assembled in any position relative to each other, as the projections in the shell will engage with the openings in the cap in a wide variety of different positions. This does away with the necessity of filing down the nipple in securing the lamp socket to a fixture. The external surface of the complete socket is

smooth and unbroken and therefore presents a pleasing appearance.

It is to be understood that the invention 50 is not limited to the precise arrangements shown in the drawings, as obviously it is immaterial which of the two parts of the socket is provided with the openings and which with the projections. 55

What I claim is:

1. An electric lamp socket having a cap and shell, one thereof being provided with a plurality of openings and the other with a plurality of coöperating projections having 60 abrupt rearward locking edges and inclined portions, the cap being elongated to allow insertion of the shell therein beyond the locking position, whereby to disengage the projections from the openings. 65

2. An electric lamp socket having a cap and shell, one thereof being provided with a plurality of openings and the other with a plurality of coöperating projections having abrupt rearward locking edges and inclined 70 portions, one of the members being elongated to allow insertion of the other member therein beyond the locking position, whereby to disengage the projections from the openings. 75

3. An electric lamp socket having a cap and shell, one thereof being provided with a plurality of openings and beyond them with an abutment and the other with a plurality of projections having abrupt locking 80 edges, the distance between the edges of said projections and the end edge of the member bearing the same being less than the distance between the outer end edges of said openings and the abutment on the other 85 member whereby said members when locked together may be disengaged by successive longitudinal and rotative movement.

In testimony whereof I have hereunto set my hand.

CLARENCE A. VETTER.
